UNITED STATES PATENT OFFICE.

NILS REIHMER, OF CHICAGO, ILLINOIS.

DESIGN FOR A MAN'S VEST.

49,196.

Specification for Design.

Patented June 13, 1916.

Application filed January 31, 1916. Serial No. 75,443. Term of patent 14 years.

To all whom it may concern:

Be it known that I, NILS REIHMER, a citizen of the United States, residing at Chicago, in the county of Cook and State of Illinois, have invented a new, original, and ornamental Design for a Man's Vest, of which the following is a specification, reference being had to the accompanying drawing, forming a part thereof.

Copies of this patent may be obtained for five cents each, by addressing the "Commissioner of Patents, Washington, D. C."

The figure is a plan view of a man's vest, showing my new design.

I claim:

The ornamental design for a man's vest, as shown.

NILS REIHMER.
